ATTORNEY.

UNITED STATES PATENT OFFICE.

GEORGE P. TILTON, OF NEWBURYPORT, MASSACHUSETTS, ASSIGNOR TO THE
TOWLE MANUFACTURING COMPANY, OF SAME PLACE.

DESIGN FOR A SPOON, &c.

SPECIFICATION forming part of Design No. 20,931, dated July 14, 1891.

Application filed June 16, 1891. Serial No. 396,520. Term of patent 7 years.

To all whom it may concern:

Be it known that I, GEORGE P. TILTON, of Newburyport, in the county of Essex and State of Massachusetts, have invented a new and original Design for the Handles of Spoons and Forks, of which the following is a full, clear, and exact description.

Reference is to be had to the accompanying drawing, forming a part of this specification, in which the figure represents a face view of a spoon having my new design embodied in the handle thereof.

The design consists of the surface ornamentation shown, which is as follows: Near the outer end of the handle appears a shield-like figure *a*, the same having the appearance of curving over at the top and being surmounted

by a figure comprising the cornucopia scroll *b*, the members of which are surmounted by foliate figures *c*. At the sides of the cornucopia figure appear the shell-like figures *d*. Below the shield-like figure *a* appear in succession the reversely-disposed foliate scrolls *e*. Inward from the foliate scrolls *e* appears the longitudinally-ranging rope-like figure *f*, which terminates at its inner end in the foliate scroll *g*. 20 25

I claim—

The design for the handles of spoons and forks herein shown and described.

GEORGE P. TILTON.
